United States Patent Office

Des. 183,457
Patented Sept. 2, 1958

183,457

ELECTRONIC PRINTING MACHINE

Frank Rudolph House, Franklin, Mass.

Application November 27, 1956, Serial No. 43,959

Term of patent 14 years

(Cl. D64—10.1)

Des. 183,457

PAGE 2

Fig. 3

Fig. 4

Fig. 1 is a front perspective view of an electronic printing machine showing my new design;

Fig. 2 is a rear elevational view thereof;

Fig. 3 is a side elevational view as seen from the right of Fig. 1; and

Fig. 4 is a side elevational view as seen from the left of Fig. 1.

I claim:

The ornamental design for an electronic printing machine, substantially as shown.
